UNITED STATES PATENT OFFICE.

WILLIAM O. ISAACSON, OF CHICAGO, ILLINOIS.

ANCHOR.

Application filed August 24, 1925. Serial No. 51,945.

This invention relates to anchors for fastening bucks into place and with regard to certain more specific features to means for temporarily and permanently anchoring 5 bucks.

Among the several objects of the invention may be noted the provision of means for temporarily holding a buck in place as a wall is being built therearound, said 10 means to be applicable to concrete, masonry and like construction; the provision of means for permanently holding the buck in place on concrete or the like at its lower end; and the provision of means for carrying out 15 the above objects requiring only a hammer as a tool for the application thereof. Other objects will be in part obvious and in part pointed out hereinafter.

The invention accordingly comprises the 20 elements and combination of elements, features of construction, and arrangements of parts which will be exemplified in the structure hereinafter described, and the scope of the application of which will be indicated in 25 the following claims.

In the accompanying drawings in which are illustrated various possible embodiments of the invention,

Fig. 1 is a front elevation of a buck set 30 in place with a wall partly built there around and the anchors applied;

Fig. 2 is a fragmentary elevation of the lower right hand corner of Fig. 1, showing portions broken away;

Fig. 3 is an ideal section taken on line 35 3—3 of Fig. 2;

Fig. 4 is a perspective view of a preferred form of permanent anchor;

Fig. 5 is a view similar to Fig. 4 showing 40 a modified form of permanent anchor;

Fig. 6 is a perspective view showing another modified form of permanent anchor and a portion of a buck in dotted lines;

Fig. 7 is a view similar to Fig. 6, showing 45 another form;

Fig. 8 is a view similar to Fig. 6, showing another form;

Fig. 9 is an enlarged fragmentary side elevation of Fig. 1, showing the temporary 50 portions of the anchoring means and showing an alternate position of portions thereof in dot-and-dash lines;

Fig. 10 is a lateral section taken on line 10—10 of Fig. 9;

Fig. 11 shows a fragmentary elevation,

taken from the inside of a buck with the buck removed, of a temporary anchor showing its tines in different positions; and

Fig. 12 is a plan view of the upper end of a temporary anchor with nails removed. 60

Similar reference characters indicate corresponding parts throughout the several views of the drawings.

Referring now more particularly to Fig. 1, there is illustrated a wooden buck 1 such as 65 is ordinarily used for doors and the like. This buck has two upright portions 3 and 5 with a top cross member therebetween. The members of bucks such as illustrated have any one of a number of cross sectional 70 shapes. The form of cross section usually employed, however, is illustrated in Figs. 3 and 10. As indicated in those figures, two outwardly extending tongues or ribs 7 are adapted to form a recess 9 for the reception 75 of the ends of bucks and tiles 11 or the like.

In constructing an apertured wall the buck 1 is usually first set into place and the wall built around it. The buck and the brick or tile and the like, are adapted to fit one another. Hence various sizes and shapes of 80 bucks are in use. The section of the buck shown in the drawings will serve illustrative purposes.

When bucks and the like are set up on concrete floors or other surfaces it is difficult to prevent their being knocked over during the course of construction. This is especially true where the floor and ceiling are formed of concrete, stone, brick or other hard material on which it is difficult to apply braces or into which it is difficult to drive nails and the like. Furthermore, it is desirable to prevent the sides 3 and 5 of a buck from being drawn or pushed inwardly after a wall is 90 built. The mortar or other bond between the buck and the wall is not enough to hold the sides 3 and 5 permanently to the wall under all conditions of use. 95

To hold the lower ends of the sides 3 and 5 100 permanently in place a preferred form of anchor clips shown in Fig. 4 is herein employed. This clip comprises two flat non-parallel legs or prongs 13 curved away from one another at points 14 at their separated outer ends. These prongs are integrally formed and are joined at their closer ends by a cylindrical portion 15. Teeth 17 are cut 105 on the upper edges of the prongs 13. The clip as a whole is formed of a sheet of spring 110

metal of approximately thirty five thousandths of an inch in thickness. This corresponds to approximately number 20 of the Birmingham wire gage.

5 The cylindrical portion 15 is adapted in bore to slidably but more or less tightly receive a nail 19. The nail 19 has a relatively large head 21 and is composed of hardened material. The cylindrical portion 15 of the 10 clip embraces the nail 19 for a substantial part of its length thereby bracing it against bending when it receives a blow.

Certain sizes of the hardened nails are 15 adapted to enter the concrete under action of blows thereon, without tending to break or bend sidewardly, although no extraneous bracing passage is employed.

The anchor clip is applied to the bottom 20 of the buck by driving the pair of prongs into the buck uprights 3 and 5. Blows from a hammer on the flush bottom sides of the prongs 13 will drive them sidewardly into the wood, teeth first. The teeth 17 facilitate driving.

25 Any number of clips may be applied to an upright in any position. The use of two of them in the positions indicated in Figs. 2 and 3 is preferable.

30 After the clips have been applied to a buck the nail carrying portions 15 protrude through or into the said space 9 between the tongues 7. The bottom edges of the clips are flush with the bottom edges of the buck (Figs. 1 and 2).

35 Next the buck is mounted in position on its (say concrete) floor. The nails 19 may or may not have been applied as shown in Fig. 4, to their cylinders 15 before the clips were driven home into the buck bottom. If

40 they were so applied, they are ready to be driven. If they were not applied they are now applied to said cylinders 15. Then by applying blows from a hammer to the heads 21, the nails may be driven downwardly into

45 the concrete (dry or wet) or other hard or soft material. The stems 19 are hardened and enter the hardened concrete more or less easily and also resist bending. Any tendency to bend is prevented by the enclosing 50 cylindrical portions 15 which, as stated, fit the nails tightly. It is preferable not to have the portions of the nails entering the concrete or other stony floor longer than the length of the cylindrical portions 15.

55 It may be noted that the pairs of prongs 13 when driven into the buck receive hammer blows, each prong bracing the other against lateral collapse. Their spring material also aids in stiffening these prongs as

60 well as the curved portions 14 thereof. The curved portions 14 also prevent withdrawal of the clips from the buck by an endwise movement thereof or of the buck.

65 After the buck 1 has been anchored down as described (Figs. 2 and 3) the bricks or

tile 11 of a wall may be built up around said buck. The lower corner brick or tile should have its lower corner, or corners broken off in order that it may clear the exposed nail heads 21 and the cylindrical portions 15 of the 70 clip whereupon the brick may be abutted into the space 9 between tongues 7 without interference. The broken away portions of the brick or tile which contain the exposed portions of the clips may be filled with mortar 75 23 or the like (Figs. 2 and 3).

It is obvious that after the buck has been anchored as described, and a wall built there around or before the building of the wall, that the side uprights 3 and 5 cannot readily 80 be moved in any direction at the floor line by a force near the floor line. However, before the wall has been built and after the buck has been anchored at the bottom as described, it is possible to apply a force at the top of the buck and thereby exert such a great leverage that the nails of the lower clips (described) may be torn from the flooring. This contingency will be provided against hereinafter.

85 At this stage there has been provided means for locating or placing a buck permanently, and means for preventing the withdrawal of the uprights 3 and 5 thereof, from a finished wall.

90 The form of anchor clips shown in Fig. 4 is to be interpreted as being illustrative.

95 In Fig. 5 is shown an anchor clip form which has only one prong 25 made of somewhat heavier material than the prongs 13 of the previous form. The top of the prong 25 is sharpened at 27 to facilitate driving and the prong is amply crimped or bent at point 29 in order to provide against sideward collapse as it is driven home into a 100 buck. The cylindrical end portion 15 is again formed with the prong 25. Other salient features of this modified form are similar to those described for the form of Fig. 4.

105 It is further to be understood herein that this invention is not limited to individual anchor clips. In Figs. 6 to 8 are shown pairs of clips compounded into twin forms.

110 Referring particularly to Fig. 6, there is illustrated a flat plate 31 adapted to fit the bottom of a buck upright. It may be provided with an aligning lip 33, but this lip is not positively required.

115 Opposite the lip 33 is integrally formed with the plate 31, an upturned ear 35. This ear 35 has integrally formed, folded over, leaves 37, which in folding form cylindrical portions 39 for slidable but tight reception of said hardened nails 19. The device is so 120 designed that the cylindrical portions assume positions corresponding to said positions of the portions 15 in the previous forms when the device is applied to a buck. The device is applied to a buck by means 130

of ordinary nails 41, applied from the bottom of the buck through holes 43 in the plate 31.

It may be noted that the device of Fig. 6 5 may be stamped or otherwise formed from a single piece of sheet metal. The ear 35, the leaves 37 and the lip 33 lie in a single plane before the forming operation.

The purposes of this last described and 10 the two subsequent forms are the same as for the forms of Figs. 4 and 5. Again only a hammer is needed for application thereof.

In Fig. 7 is shown a modification of the twin form in which a flat plate 45 has 15 formed therewith an upturned portion 47 and a backturned portion 49. The plate 45 and portions 47 and 49 enfold a strip of wood 51. The strip of wood 51 and its en-folding metal are drilled to receive the nails 20 19 in a manner such as has been described. The plate 45 is nailed to the bottom of a buck upright by nails 41 passing through holes 43 in the plate.

In Fig. 8 a plate 53 is nailed to the buck 25 uprights by nails 41 through holes 43. An extending portion 55 of the plate 53 has tubular portions 57 drawn integrally therewith or otherwise formed therewith and adapted to receive the fastening nails 19.

30 In the forms of this anchor shown in Figs. 6 and 7 it is necessary to break more or less of the whole lower corner of the brick or tile placed at the anchoring portion for reasons obviously shown in said Figs.

35 6 and 7.

Reference has been made hereinbefore to 40 moving the upper end of the buck before the wall therearound is completed. This may easily be done, despite the anchoring effect of the described lower anchors, because of the great leverage which may be applied. In order to hold the buck in place 45 solidly while the wall is under construction and while it is subjected to chance blows and the like by workmen, wheelbarrows and the like, an upper temporary and removable anchor is herein provided and described. Figs. 1, and 9 to 12 illustrate this removable device or devices.

50 Each removable anchor comprises a pipe or tube or arm 59 (Fig. 9) into one end of which are inserted two strips of preferably stout malleable metal 61. The tube 59 is flattened and pinched tightly on these strips 55 61. The strips 61 are led from the tube 59 sideways and twisted near their ends so that 60 their planes are parallel to the length of the tube 59. The ends of the strips are then formed as short cylindrical portion 63 65 adapted to receive hardened nails 19 for purposes of fastening the tube 59 to a concrete or other like floor, wall, ceiling, or other stony structure. The cylindrical portions 63 brace the hardened nails 19 against bending as they are driven into the concrete,

which concrete is usually placed and dry, as well as hard. Hence an anchoring tube or pipe 59 may readily be made fast to a ceiling or other structure, even though the structure is stony and/or hard. The hard 70 material of which the ceiling is composed does not deter the anchoring action because of the features described.

Slipped on the tube or pipe 59 is a spring saddle 65 which has a curved back 67 and 75 laterally extending more or less flat ears 69. The saddle is approximately equal in width to a buck timber (see Figs. 1 and 10). The ears 69 have holes in them adapted to receive the pipe or tube 59 when the saddle 80 portion 67 is in an abnormal or strained position. Hence after the ears 69 are passed over the tube 59, the saddle 65 in attempting to return to an unstrained position causes 85 the ears 69 to grip the pipe 59 thereby holding the saddle in a given position. In order to move the saddle on the tube 59, it is only necessary to push one of the ears in a direction toward the other and the strained relationship of parts is assumed, whereupon 90 movement may be accomplished because the ears 69 do not bind. The tube 59 is capped at one end by a blind nipple or other device 71 for purpose of holding the saddle from being inadvertently slipped off and 95 for providing a tube end without sharp corners or burrs.

The saddle 65 is provided on the tube 59 to furnish adjustable means for fastening the anchor tube to a buck after the tube 100 has been nailed to a ceiling or the like by means described. The reason for this is that the distance from the tops of various bucks to ceilings of various heights is not constant. The saddle is fastened to the buck by the 105 following means:

Near the ears 69 but on the saddle 65 are crimped the pairs of passages 73 adapted to laterally receive clamping wires 75. The wires 75 are rather heavy and are made 110 of spring material. They are rotatably mounted in the openings 73. Each wire 75 comprises the portion passing through the openings 73 equal in length to the width of the saddle piece 65. At one side of the saddle a branch or leg 77 of each wire normally descends straight downwardly, while on the other side a short branch or leg 79 reaches out horizontally away from pipe 59 (see dot-and-dash lines, Fig. 9 and lower wire, Fig. 11). Each leg 79 is provided with a short horizontal finger 81 which reaches in to within the limits of the saddle width. Each leg 77 is provided with a short sharpened prong 83 which reaches in to 115 within the limits of the saddle width.

The wires 73 and parts thereof are rotatable from the position of the lower wire of Fig. 11 to the position of the upper wire in said figure. The legs 77 are also adapt- 120 125 130

ed to spring to the dashed line position shown in Fig. 11 and yet be able to spring back into the solid line position. The stated positioning is done manually.

- 5 To apply an anchor the tube 59 is nailed to the (say) ceiling as described, near the front and/or rear edge of a buck (Figs. 1, 9 and 10). The legs 77 of wires 75 hang down as shown in dashed lines (Fig. 9), while the legs 79 remain horizontal, due to gravity effects. The saddle 65 is positioned with regard to the front or rear side of a buck timber in such a manner that the fingers 81 reach in behind one of the said tongues 7. The length of the leg 79 is such that the finger 81 amply clears the tongue 7 (dashed lines, Fig. 9). Then by first springing the legs 77 outwardly (dashed lines, Fig. 11) and then drawing said legs 20 77 upwardly (full lines Figs. 9 and 11) the fingers 81 may be clamped to one of the tongues 7. The first springing action is brought about to clear the prong 83 of the buck edge.
- 25 After the clamping position of the fingers 81 is reached, the legs 77 are drawn up slightly more to ensure a tight grip. A hammer blow or more is then applied to the top of prong 83 and it is driven home into the side of the buck (Fig. 19). Hence the buck is anchored to the tube 59 and therefore to the ceiling when the nails 19 are applied. It is to be understood that the saddle 65 and tube 59 may be first applied to the buck and then by loosening the ears 69 by pressure the tube 59 may be slipped up to a position where the nails 19 may be applied to the ceiling through cylinders 63. The order of operations is left to the choice of 30 40 an operator.

Two anchor assemblies may be applied to a buck as illustrated in Fig. 1. Another hole 88 drilled into one of the upper ears 45 69 is adapted to receive a snap hook 85 of a chain 87. The chain is made amply long and leads to a hook 89 fastened into the upper end of the other tube 59. By fastening the chain as described the anchoring structure is well braced. Slack may be taken up 50 in the chain by changing links at hook 89 or by moving the saddle to which it is attached in a downward direction by pulling down on the upper ear of said saddle, that is, before the described clamps have been made fast.

Removal of the anchors is readily accomplished by use of the claw of a hammer or other prying tool under the leg 77 (Fig. 10). This frees the prong 83 and the fingers 60 65 81 may be released. With the aid of the leverage afforded by tubes 59 the T-headed portions comprising strips 61 may be easily loosened from the ceiling. It is assumed that at this stage the wall has progressed to an elevation near or over the top member of

the buck. If the wall elevation has passed the elevation of the fingers 81, no difficulty is encountered as these fingers are short and are easily withdrawn. They do not seriously interfere with the placing of brick or tile either.

It is herein intended that the anchor rods 59 and parts thereto appertaining as well as the permanent anchors may be used to brace a buck or the like at its top edge and to 75 a side wall or from its side edges to a floor and other like applications of which Fig. 1 is illustrative.

It is further to be understood that the word "buck" shall include in its meaning 80 any frame for arches and for apertures in walls and the like.

The advantages of the new construction herein shown are almost obvious. An adjustable anchor is provided for holding 85 bucks while permanently anchoring them. One adjustable anchor may readily be removed and a permanently set buck remains fastened to its surrounding wall.

Only a hammer is needed for the application of the anchoring means and for its removal. It is quickly applicable in the hardest of set concretes, stone and the like and is economical to construct.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawings shall be interpreted as 100 105 illustrative and not in a limiting sense.

I claim:

1. An anchor for bucks and the like comprising a device adapted to be fastened to a buck and means formed with said device whereby it may be fastened to a stony material by applying blows only, said means comprising an elongated cylindrical portion and a hardened nail slidably fitting within said portion, said cylindrical portion being adapted to support the nail in a predetermined position with respect to said material. 110 115

2. Means for anchoring a member to another member, the latter being composed of relatively brittle material, said means comprising a cylindrical portion associated with said first-named member and a hardened nail slidably fitting said portion and adapted to pass therethrough under action of applied blows, said cylindrical portion being adapted to support the nail in a predetermined position with respect to said material as the nail is driven home. 120 125

3. The construction comprising an anchored member and a second relatively brittle member to which said first-named mem- 130

ber is anchored, anchoring means comprising a hardened nail adapted to pierce said brittle material, and a cylindrical portion associated with the anchored member in which said nail is positioned and supported.

4. The construction comprising an anchored member and a second relatively brittle member to which said first-named member is anchored composed of concrete, anchoring means comprising a hardened nail adapted to pierce said concrete, and a supporting cylindrical portion associated with the anchored member in which said nail is finally positioned and in which said nail is supported as it is applied to the construction.

5. The construction comprising an anchored member and a second concrete member to which said first-named member is anchored, anchoring means comprising a hardened nail adapted to pierce said concrete upon application of driving blows to the nail, and a cylindrical portion associated with the anchored member in which said nail is positioned when finally placed in the construction and in which said nail is supported as it is driven into place.

In testimony whereof, I have signed my name to this specification this 18th day of August, 1925.

WILLIAM O. ISAACSON.
